DESIGN FOR A CASING FOR A THERAPEUTIC LAMP

Frederic Wommer, Carver, Minn., assignor of one-half to H. Lee Reynolds, Pittsburgh, Pa.

Application July 24, 1939, Serial No. 86,204

Term of patent 7 years

To all whom it may concern:

Be it known, that I, Frederick Wommer, a citizen of the United States, residing at Carver, in the county of Carver and State of Minnesota, have invented a new, original, and ornamental Design for a Casing for Therapeutic Lamps, of which the following is a specification, reference being had to the accompanying drawing, forming part thereof, and in which

I claim:

The ornamental design for a casing for a therapeutic lamp, substantially as shown.

FREDERIC WOMMER.
